US00D757467S

(12) **United States Design Patent**
Do et al.

(10) **Patent No.:** US D757,467 S
(45) **Date of Patent:** ** May 31, 2016

(54) **DISPLAY UNIT**

- (71) Applicant: **Samsung Electronics Co., Ltd.**,
Suwon-si (KR)
- (72) Inventors: **Kyoung-Sub Do**, Seoul (KR); **Seo-Gyun Kim**, Suwon-si (KR); **Sung-Su Park**, Seoul (KR)
- (73) Assignee: **Samsung Electronics Co., Ltd.**,
Suwon-si (KR)

(**) Term: **14 Years**

(21) Appl. No.: **29/510,463**

(22) Filed: **Nov. 28, 2014**

(30) **Foreign Application Priority Data**

Jun. 5, 2014 (KR) 30-2014-0027687

(51) **LOC (10) Cl.** **06-06**

(52) **U.S. Cl.**
USPC **D6/678**

(58) **Field of Classification Search**

USPC D6/657, 661, 661.3, 663, 668, 672, 678,
D6/691, 691.3; D14/340; D19/90; D20/10,
D20/43

CPC A47B 67/00; A47F 5/0018; A47F 3/0404
